HYDRAULIC LOG BARKER WITH SELF-LUBRICATING SEALING MEANS

Frank H. Swift and Guy R. Dodson, Portland, Oreg., assignors to Crown Zellerbach Corporation, San Francisco, Calif., a corporation of Nevada

Application April 8, 1946, Serial No. 660,458

4 Claims. (Cl. 144—208)

1

This invention relates to hydraulic log barkers. In connection with the preparation of wood in rough log form it is often desirable, as, for example, in the reduction of the wood to pulp for use by the paper industry, to remove the bark. The application of a jet of water under high pressure to the surface to be debarked has proven very effective and apparatus for carrying out this operation is now in general use in several different specific forms. In such apparatus the jet is directed against each part of the log surface from which bark is to be removed and it is therefore desirable that the log being treated and the nozzle which forms and directs the jet be relatively movable for practical operation.

Various machines have been designed in which such relative movement is accomplished either by movement of the log or the jet or both. In some cases, the log is rotated as by a lathe while the jet moves longitudinally to follow the spiral path on the log surface which is the component of the rotary and longitudinal motions. In other cases the log is rotated step by step and the jet is moved lengthwise to remove straight areas of bark from end to end of the log during the intervals between its intermittent rotating movement. These, as well as other methods which have been employed in an endeavor to subject the entire surface of the log to the action of the jet, have been found lacking in speed and efficiency because of the time required to set up each log to be treated. Such methods are also undesirable because logs are not of uniform size and shape and are therefore not readily adaptable to handling by machinery in which they must be gripped and turned. Many logs have broken, rotted, or otherwise non-uniform ends making them unsuitable for mounting in a handling device of the lathe type, and in some cases it is necessary to debark logs, half logs, quarters, slabs and other shapes all in the same machine.

The most practical form of debarking can be accomplished by a so-called ring type machine, such as is disclosed in the patent to Frank H. Swift, No. 2,422,757, issued June 24, 1947, entitled "Hydraulic Barker." Such a machine includes a nozzle traveling in a circular path to direct a jet radially inwardly. Any log or log section passing through the circle described by the nozzle is therefore subjected throughout its entire surface to the effect of the jet even though the log itself is not turned or rotated. This type of machine lends itself quite readily to use with conventional mill operations where logs are moving in end-to-end relationship as on conveyors.

2

Such a line or string of logs may be directed through a ring type barker without stopping and without regard to differences in their length, shape and the other individual characteristics which must be considered in chucking or setting up logs in other types of barking machines.

The construction of a ring type machine of the kind herein referred to however has heretofore provided problems arising principally because of its great size and the high fluid pressure which it must be capable of withstanding. For example, to accommodate logs of even thirty inches in diameter the nozzle which produces the barking jet must describe an annular path having a diameter of at least thirty-six inches. This requires annular hoop-like members of hollow construction capable of withstanding internal pressures in the order of a thousand or fifteen hundred pounds per square inch. It also requires such members to be relatively rotatable so that some form of packing or sealing means must be provided between them for permitting rotation without material loss of the liquid under pressure which they contain and direct toward the nozzle. It has been found that conventional sealing means are impractical for this purpose because they depend upon pressure to create effective seals and the pressure required is so great that the sealing means act as a brake which prevents by friction the relative rotation of the parts between which the seal is provided.

It is, therefore, an object of the present invention to provide a hydraulic log barker of the ring type in which large, relatively movable pressure sustaining parts are designed and connected by sealing means which overcome the difficulties heretofore encountered in machines of this character.

Another object of the present invention is to provide a method of sealing and a seal for use in hydraulic log barking machines which may be lubricated by the same water that is employed for barking purposes and which includes means for accurately adjusting the quantity of water employed for lubrication.

Further and more specific objects and advantages of the invention are made apparent in the following specification in which reference is made to the accompanying drawings for a disclosure of the invention in one of its preferred forms.

In the drawings:

Fig. 1 is a front elevation of a hydraulic log barking machine embodying the present invention and illustrated with parts broken away and

parts shown in section to disclose structural details;

Fig. 2 is a similar view in rear elevation of the same machine;

Fig. 3 is a greatly enlarged fragmentary sectional view taken on the line III-III of Fig. 1;

Fig. 4 is an enlarged view of a portion of the sealing means shown in Fig. 3;

Fig. 5 is a sectional view taken on the line V-V of Fig. 1; and

Fig. 6 is a partial sectional view comparable to the section shown in Fig. 3 but illustrating a modified form of the invention.

The log barking machine which is generally illustrated in Figs. 1 and 2 of the drawings is of substantially annular construction so that it provides a central open space through which logs may be passed in the direction of their length. Any conventional log handling equipment, such as conveyers or skids, not shown, may be employed for advancing the logs through the machine. Such equipment, whatever form it may assume, preferably does not extend through the opening of the machine as it is desirable that the entire periphery of the log be exposed to the action of water jets which are directed against it by revolving nozzles, shown at 10 in Fig. 2 of the drawings, as the log passes through the central opening of the machine.

The entire machine may be supported on any convenient horizontal surface by a base 11 which in turn supports a vertically extending rigid annular frame member 12 herein illustrated as formed integrally with the base casting. A stationary circular manifold 13 is carried by the annular frame 12 and is supported with relation thereto by means of a plurality of cap screws 14 which, as shown in Figs. 1 and 3, extend through brackets 15 extended radially inwardly from the frame 12. Cap screws 14 are received in tapped holes, not shown, formed in the face of the manifold 13. A rotatable manifold 16, also generally annular in shape, circumscribes the stationary manifold 13 and carries the nozzles 10 which direct jets of water radially inwardly and onto the surface of a log passing through the machine. An inlet pipe 17 best shown in Fig. 1 communicates with the hollow interior of the stationary manifold 13 and is provided with a flange 18 at its outer end by means of which it may be connected with a conduit, not shown, for communication with a source of water under high pressure. The stationary manifold 13 has a plurality of circumferentially arranged outwardly directed ports 19 and the rotatable manifold 16 has corresponding ports 20 which are directed radially inwardly and which are formed in a relatively narrow inwardly disposed annular portion 21. The manifolds are assembled with the ports 19 and 20 in alignment so that water under pressure directed to the interior of the stationary manifold 13 is readily communicated to the rotating manifold during its rotation. From the interior of the rotating manifold, the water under pressure is directed through integrally formed hollow arms 22 which support and communicate with the nozzles 10. While there are two arms 22 and two nozzles 10 herein illustrated as disposed at diametrically opposite portions of the rotatable manifold, it should be understood that a single such nozzle would be operable for the purpose described, though two or even more nozzles equally spaced throughout the periphery of the rotatable manifold are preferable as, with a greater number of nozzles, the force of the jets which

they produce has less tendency to displace the log from its path of movement through the machine. Furthermore, with the greater number of nozzles the log may be advanced more rapidly through the machine with assurance that its entire surface is subjected to the influence of the high pressure jets.

Each of the nozzles is a tubular and preferably tapered structure which may be secured to the end of its supporting arm 22 as by cap screws illustrated at 23. The nozzle opening may conveniently be a row of small orifices 24 aligned in a plate 25 secured as by screws 26 to the end of the nozzle. As best illustrated in Fig. 3, the nozzle ends may support an annular guard plate 27 which is aligned with a similar plate 28 secured to and supported by the stationary manifold 13. The annular guards 27 and 28 are of substantially the same internal diameter as the manifold 13 and cooperate therewith in defining the passage through which the logs move as they are subjected to the action of the debarking jets.

The rotatable manifold 16 is supported by a plurality of rollers 30, shown in Figs. 1 and 2 as three in number. The outer surface of the rotatable manifold is machined to form spaced tracks 31 and an intermediate ring gear 32. The rollers 30 are centrally grooved as shown at 33 to clear the ring gear 32 as they support the manifold by engagement with its tracks 31. Any suitable means may be employed for driving the manifold 16. For example, a spur gear 34, rotated by motive power, not shown, meshes with the ring gear 32 to impart rotary motion to the manifold 16 thereby causing the nozzles 10 supported by it to revolve about the central open portion of the machine through which the logs are passed. Each of the rollers 30 is supported for rotation on a shaft 35 by suitable anti-friction bearings, not shown, and the shafts 35 are supported in brackets 36 which are adjustably secured to the main frame 12. In Figs. 1 and 2, the adjustable connection between the roller brackets 36 and the main frame is shown as a plurality of cap screws 37 which pass through elongated openings 38 (see Fig. 3) in the brackets for clamping the brackets to the face of the frame 12. Adjusting screws 39 (in Fig. 2) may be employed to vary the positions of the brackets before the cap screws 37 are tightened and set screws 40 (Fig. 1) which bear against the frame 12 may also be employed for definitely fixing the position of the rollers before the brackets are firmly secured by tightening of the cap screws 37. By a proper adjustment of the three rollers shown, the rotatable manifold may be brought into its intended position where it is concentric to the stationary manifold and where its ring gear meshes properly with the driving spur gear 34.

By reason of the construction herein described, both of the manifolds 13 and 16 are generally tubular in shape and of relatively small cross sectional dimensions so that they are readily capable of withstanding extremely high pressures without resorting to unusually heavy construction. The manifolds are spaced from each other to enable the one to rotate readily and therefore a seal must be provided to prevent the escape of liquid under pressure from the space between them. Because of its large size, such a seal must include a large area of contacting surfaces with the attendant danger of excessive friction.

The machine of the present invention includes two different types of sealing means, one being 75 of the gland type between relatively stationary

parts and the other being of the flat contacting surface type between relatively rotating parts. The latter type of seal requires lubrication for satisfactory operation as, unless it is adequately lubricated under the existing conditions of high pressure, the friction created will be so great as to prevent operation of the machine with any reasonable source of power. With the combination of sealing means herein employed by the present invention, the flat contacting faces of the seal between the rotating parts are lubricated by water which is permitted to leak or flow from the supply of water under high pressure within the manifolds and thus to pass in a quantity only sufficient for lubricating purposes between the sealing surfaces. This is accomplished by the structure illustrated in Figs. 3 and 4 which includes a pair of annular hardened plates 42 secured to the opposite sides of the rotatable manifold 16 adjacent its inner edge, and at its reduced portion 21. These plates may be secured in any suitable manner or may be formed by the deposition of hard metal by the electric welding process, the exposed surface being ground flat after depositing of the metal.

Annular seal rings 43 are carried by non-rotatable ring blocks 44 for sealing contact with the plates 42, and the blocks 44 are mounted to float or slide to and away from the plates 42 on the rotating manifold in order to vary the sealing pressure at the contacting surfaces between the plates 42 and rings 43. The sealing rings may be constructed of any material capable of lubrication by water such as a composition known as "Micarta" or various water lubricated bronzes, and they may be secured to the ring blocks by screws, one of which is indicated at 45 in Fig. 3. It is also desirable that the rings 43 be embedded in a suitable plastic adhesive material. The space between each of the ring blocks 44 and the stationary manifold 13 is sealed as by packing 46 adapted to be compressed by packing glands 47. For convenience in construction, the ring blocks 44 may be mounted in a slightly different manner, as is apparent in Fig. 3 of the drawings, where the ring block shown to the left overlies an integral flange 49 of the manifold 13 while the ring block on the right overlies a flange 50 secured to the manifold as by cap screws 51. Set screws 52 are provided to bear against the glands 47 on both sides, the set screws to the left being threaded through a flange 53 secured by cap screws 53' to the frame 12 and the set screws to the right being threaded through a flange 54 secured by cap screws 55 to the flange 50. The set screws 52 are accessible from the front and rear of the machine as illustrated in Figs. 1 and 2 and those which are disposed behind the brackets 15 are made accessible by the provision of suitable openings 56 formed in the brackets. With the set screws suitably adjusted, the packing 46 may be sufficiently compressed to prevent leakage between the ring blocks 44 and the stationary manifold 13 and still permit floating movement or adjustment of the blocks 44 to vary the pressure between the sealing faces of the plates 42 and the rings 43. The pressure applied at these faces is critical as it is desired to permit the escape of sufficient water between these faces to insure adequate lubrication so that too much pressure will prevent lubrication while insufficient pressure will result in excessive leakage.

In order to obtain an extremely sensitive adjustment of pressure some form of fluid pressure means is disposed behind each of the ring blocks 75

44. For example, as shown in Fig. 3, each ring block 44 is backed by a resilient annular tube which may be made of rubber or other similar material as indicated at 57. The backs of the blocks 44 are preferably concave to form a seat for the tubes 57 and the tubes are backed up by annular shells 58, one of which bears against the rigid part 53 and the other against the part 54. Introduction of fluid under pressure into the resilient tubes 57 therefore urges the ring blocks 44, which carry the sealing rings 43, toward the plates 42 and the pressure applied to the contacting surfaces of the seal is subject to variation which depends upon the amount of pressure introduced into the tubes 57. Thus, as may be seen in Fig. 4, the water under high pressure which tends to escape in the direction of the arrow a between the stationary manifold 13 and the rotating manifold 16 exerts pressure in opposite directions on the several opposed surfaces of the stationary manifold, the rotating manifold and the ring block 44. Depending upon the balance of pressures on these surfaces, the water will tend to escape to a greater or lesser degree between the flat contacting sealing surfaces. The balance of pressure should be sufficient to permit an escape of water in more than adequate quantities for lubrication so as positively to insure lubrication on the contacting faces under all conditions. To prevent the escape of a greater quantity of water, the fluid pressure within the tubes 57 may be adjusted until the escaping water is reduced to just sufficient to insure adequate lubrication.

35 Means for introducing fluid under pressure into the tubes 57 is illustrated in Figs. 1, 2 and 5, wherein the tubes are shown as provided with suitable inlet fittings 69 which are connected together by a branch pipe 61 which, as illustrated in Fig. 5, may pass through a groove 62 formed in the stationary manifold 13. A supply pipe 63 also communicating with the branch pipe 61 leads to a source of fluid under pressure such, for example, as a small pump and reservoir not shown. 40 Oil has proven a satisfactory fluid for this purpose although other fluids may be employed.

45 A modified type seal is illustrated in Fig. 6 of the drawings wherein a single resilient tube 57 is employed for applying the necessary pressure to the two seals on opposite sides of the rotatable manifold. In this modification, the floating ring block 44 is omitted from one side of the manifold and replaced by a stationary block 65 secured directly to the manifold 13 as by cap screws 66. As the rotating manifold 16 is capable of slight movement from side to side, the single tube 57 will urge one of the seal rings 43 against the manifold and at the same time will urge the manifold itself against the opposite seal ring, thus producing the required pressure at all sealing surfaces.

65 In operation, water, under sufficient pressure to remove bark from the logs to be treated, is introduced through the inlet pipe 17 and passes from the stationary manifold 13 to the rotating manifold 16 and out through the nozzles 10 which direct it onto a log passing through the annular structure. The pressure required for barking logs is so great that the large annular seals 43 would prevent relative rotation of the manifolds unless they were adequately and continuously lubricated. Therefore, the fluid pressure introduced to the resilient tubes 57 is carefully regulated to the value where just a slight quantity of water, from within the manifolds 13 and 16, is permitted to

escape between the sealing surfaces and in so escaping to serve as a lubricant for the seals.

We claim:

1. In combination with a hydraulic log barker comprising a stationary tubular annular manifold adapted to receive water under pressure, a similar larger manifold circumscribing and spaced from the first manifold, means supporting the larger manifold for rotation, both manifolds having radially disposed ports registering for the transmission of water to the rotating manifold, and nozzles carried by the rotating manifold for directing the water against a log to be barked, means for sealing the space between the manifolds, including seal members carried by the stationary manifold and contacting opposite sides of the rotating manifold.

2. In combination with a hydraulic log barker comprising a stationary tubular annular manifold adapted to receive water under pressure, a similar larger manifold circumscribing and spaced from the first manifold, means supporting the larger manifold for rotation, both manifolds having radially disposed ports registering for the transmission of water to the rotating manifold, and nozzles carried by the rotating manifold for directing the water against a log to be barked, means for sealing the space between the manifolds, including seal members carried by the stationary manifold and contacting opposite sides of the rotating manifold, and means for applying pressure to said seal members.

3. In a hydraulic log barker, an annular stationary manifold for the reception of water under high pressure, a similar rotatable manifold circumscribing the stationary manifold and carrying means for directing jets of water inwardly onto the surface of a log passing through the manifolds, means for transmitting water from the stationary manifold to the rotating manifold, a seal between the manifolds comprising, a pair of annular blocks carried by the stationary manifold on opposite sides of the rotatable manifold, a seal between each of said blocks and the stationary manifold to prevent leakage therebetween and permit the blocks to be adjusted toward the rotating manifold, annular sealing rings carried

one by each of said blocks and bearing against the sides of the rotatable manifold to form a seal therewith, and fluid pressure means acting against said annular blocks for varying the contact pressure at said last named seal.

4. In a hydraulic log barker, an annular stationary manifold for the reception of water under high pressure, a similar rotatable manifold coaxial with said stationary manifold and carrying means for directing jets of water inwardly onto the surface of a log passing through the manifolds, means for transmitting water from the stationary manifold to the rotating manifold, a seal between the manifolds comprising, a pair of annular blocks carried by the stationary manifold on opposite sides of the rotatable manifold, a seal between each of said blocks and the stationary manifold to prevent leakage therebetween and permit the blocks to be adjusted toward the rotating manifold, annular sealing rings carried one by each of said blocks and bearing against the sides of the rotatable manifold to form a seal therewith, and fluid pressure means acting against said annular blocks for varying the contact pressure at said last named seal.
